182,000

COMBINED BOTTLE AND CLOSURE CAP

Ray R. Reed, Blythe, Calif.

Application March 12, 1956, Serial No. 40,573

Term of patent 14 years

(Cl. D58—8)

Fig. 2.

Fig. 1.

Fig. 3.

Fig. 1 is a side elevational view of a combined bottle and closure cap with the cap removed and showing my new design.

Fig. 2 is a top plan view thereof.

Fig. 3 is a side elevational view thereof, shown in closed position.

The surface below the cone is substantially flat and plain.

I claim:

The ornamental design for a combined bottle and closure cap, substantially as shown and described.
